UNITED STATES PATENT OFFICE.

T. REEVE, J. REEVE, AND S. M. TYLER, OF BROOKLYN, NEW YORK.

IMPROVED MODE OF OPERATING THE MECHANISM OF PRINTING TELEGRAPHIC MACHINES.

Specification forming part of Letters Patent No. 21,024, dated July 27, 1858.

To all whom it may concern:

Be it known that we, THOMAS REEVE, JOSEPH REEVE, and SIDNEY M. TYLER, all of the city of Brooklyn and State of New York, have made certain improvements in or on a telegraphic instrument invented by Edmund F. Barnes, and designated as an "Embossing Self-Adjusting Telegraph;" and we do hereby declare that the following is a full, clear, and exact description thereof, reference being had to the accompanying drawings, and to the letters of reference marked thereon, and making a part of this specification, like letters being generally used as those in said Barnes' application to designate like parts of such instrument.

The invention of said Barnes consists of a telegraphic instrument making printed letters, which can be used under disadvantageous circumstances, and which by causing the type-wheel and circuit-breaker to return to a given starting-point after printing such letter is self-adjusting or self-regulating. Our improvements thereon refer to the mechanical arrangement or devices for helping carry such invention into practice. In Barnes' invention the finger-keys used for transmitting were arranged upon a semi-cylindrical plate, placing them in a position inconvenient for the operator to see and manipulate, and the connection between such keys and the swing-frame, so called, was by or partially by a sliding contact.

These difficulties or objections we have obviated by arranging the keys on a flat plate in a semicircular form, and thereby also obtaining a direct connection between them and the swing-frame.

Figure 1 shows such arrangement, and Fig. 2 illustrates the direct connection between the keys and swing-frame.

As seen in Fig. 2, the keys *a a* pass through the key-board *A* and swing-frame *B* and the fixed plate underneath it, such keys being smaller at their lower end, which passes through the swing-frame, &c. When any key is depressed a shoulder upon it strikes against the swing-frame and presses it directly down, and, as in Barnes' invention, acts through the connections 3 31 32, rod *c*, and clutch *b*, to throw up the clutch-wheel *g* into contact with the clutch *f* to revolve the hollow shaft *C*, and

the circuit-breaker arm *d* connected therewith, until such arm shall come in contact with the extremity of any depressed key. The key is thrown up by the spring 1 about it, and the spring 6 carries back the swing-frame, disconnecting *g* and *f*.

In Barnes' invention, also, the shaft *e*, Fig. 2, within the hollow-shaft *C*, was square at that part on which the clutch-wheel *g* and the bar *m'*, with its clutch-pins 12 12, moved up and down, and the clutch-pins 12 12 were quite near the shaft. It therefore required a strong spring, 6, to throw up the swing-frame and carry down the clutch-wheel *g* whenever a key was relieved from pressure, and the action of the parts was rendered more difficult and less prompt than was desirable.

Our improvements consist in substituting a round shaft in place of the square one, and in placing the clutch-pins 12 12 at a greater distance from the shaft, at or near the distance of the semi-diameter of the wheel *g*. As the shaft *e* is continually revolving while the wheel *g* and its connections are moved up and down, the square form of the shaft rendered the movement of those parts less quick and easy than with the use of the round shaft substituted by us, and the friction of leverage is also decreased by carrying the points 12 12 a greater distance from the shaft *e*.

Our principal improvement consists in the arrangement of an independent friction upon the type-wheel shaft *T*, so as to give a more prompt and instantaneous action to such shaft and the type-wheel upon it whenever the escapement-wheel *O* is released by the action of the magnet. This shaft, like most of the others in the instrument, is so arranged as to the gearing upon it that the gearing may rotate while the shaft is at rest, and the shaft, when revolved, is caused to revolve by a friction-plate and box, the latter of which is connected to such shaft through a coiled spring, *r'*, one end of which is attached to the spring-box and the other to the shaft *T*. Such spring is set up to and held at a given tension within its box, and the friction causes such spring to wind about half a revolution farther, but cannot increase its tension beyond a given point. These features are necessary for the type-wheel shaft, whatever the arrangement of its friction.

In Barnes' invention the shaft was revolved by a friction, the arrangement of which is shown in Fig. 3, consisting of a spring, S'' , forcing a face-plate, f' , against another continually-revolving plate or nut, f'' , fixed to the shaft T , the pinion X' , to which is connected the support for the spring-box, also resting upon the nut X'' , which was fixed to the shaft. The result of such arrangement was to create friction upon the surfaces of f'' and X'' , and this friction, when the action of the magnet liberated the escapement-wheel O , tended to produce a sluggish movement in such type-wheel shaft and the necessary revolutions of the type-wheel.

Our improvement consists in constructing an independent friction, and is more plainly seen in Fig. 4, which is an enlarged sectional view of the type-wheel shaft T of Fig. 2. The change in position of the pinion X'' and spring-box r' is not material, the arrangement of the friction being most important. Upon the shaft T is the friction-box S' , connected therewith, as described above, by the spring r' , and about this shaft we place a hollow shaft or sleeve, T' , which carries the pinion X' and the friction-plate within the box S' . Upon the friction-box S' is a top plate, p' , which is fastened by screws or otherwise to the box S' . Within this box is the friction-plate O' , which is fast to the hollow sleeve T' , upon which works also the set-screws S''' , and between the plates p' and O' is a washer, $o o$, which may be a soft piece of common leather. The spring S'' , which is adjusted by the set-screws S''' , rests upon the top of the plate p' , and its power is exerted to force or draw up the friction-plate O' against the inside of the top plate, p' , and thus secure the desired friction. By this arrangement the spring S'' acts against two fixed points, the plate p' and the set-screws S''' , hollow sleeve T' , instead of against two points on the shaft T , and therefore does not produce or increase friction on the shaft T , the only friction on which is that produced by the weight of such sleeve and the parts thereon on the loose washer q .

Whenever the receiving parts of the instrument are put in motion the pinion X' and the hollow shaft or sleeve T' are constantly rotating, which at first revolves the shaft T , and the friction tends to wind up the coiled spring to a certain point, after which the friction-plate rotates on its washer, and the shaft T stands at rest. As the shaft T is thus substantially relieved from all friction, except at its bearings, it instantly submits to the influence of the spring r' the moment the arm of the magnet disengages a tooth of the escapement O and revolves the type-wheel to its proper letter, according to the number of pulsations given at the escapement.

Another improvement consists in so arranging a part of the gearing upon the power-shaft, so called, that only a portion of the working parts of the instrument or the whole may be operated, as desired.

Each of said Barnes' instruments is adapted

both for transmitting and receiving messages, but only one of these operations is performed at the same time, and the particular parts used for such several purposes are distinct from each other, though moved by a common power, and when used for transmitting any message there is no actual labor, an office being performed by the receiving portions of the instrument.

Our improvement consists in arresting the movement or revolution of the receiving parts of the instrument while the operator is engaged in transmitting a message, thus requiring of such operator less manual labor to work the machine, as a part is worked more easily than the whole when his attention is most demanded in transmitting, and again causing such receiving parts of the instrument to be instantly set in motion when required.

Our improvement is shown in Fig. 2 on shaft C . Instead of placing the wheel w (shown in section) and Y'' directly upon the shaft C , as was done by said Barnes, we place such wheels upon a sleeve setting over the shaft C , and which easily allows such shaft to revolve within it and without rotating such wheels with it. Such sleeve and its wheels rest upon the shoulder or plate t' , which is fixed to and revolves with the shaft C . Through this plate t' is a small hole, a number of like small recesses, t'' , being made in the under side of the wheel Y' . Underneath this plate t' is a movable collar, W'' , which has upon its upper surface a pin resting in the hole in the fixed plate t' , and which can also be made at pleasure to pass into the holes t'' in the wheel Y' . A forked rod, W''' , embraces such movable collar W'' , and moves on a fulcrum, Z'' , and to the other end of it connects the rod X'' , which passes through the upper plate, A , and may be moved with a knob, K . When such knob is raised, as shown by the heavy lines in the drawings, the clutch W'' is forced down, carrying with it the pin t'' from out of the pinion Y' and disconnecting such pinion and the hollow sleeve to which it is attached from the shaft C , and thus allowing the parts of the instrument moved by the pinion on such sleeve to stand at rest, so that only such parts as are worked from the wheel $1b$, and which are the transmitting portions, are in operation. As soon as the operator has sent his message and is ready to receive a communication from another place he presses down the knob K , which throws up the clutch-collar W'' and connects the hollow sleeve and its gearing with the shaft C , and causes the receiving parts of the instrument to be set in operation. Thus the simple elevation or depression of the knob K disconnects or connects the receiving portions of the instrument which are the greatest in number, and demands from the operator the least exertion of manual labor at the time when his attention is required in sending a message.

What we claim as our invention, as improvements in the mechanical arrangement of said Barnes' telegraphic instrument, is

1. Arranging the keys in a flat plate or keyboard in a semicircular form, substantially as described, securing thereby a direct connection between such keys and the swing-frame.

2. Applying the points or clutches 12 12 at a distance from the shaft *e*, and in connection therewith making such shaft a round instead of square, for the purpose set forth.

3. The use and application of an independent friction, constructed substantially as described, upon the type-wheel shaft, to secure, in connection with the coiled spring, more prompt and instantaneous action to such shaft

and the type-wheel thereon whenever the magnet releases the escapement-wheel *O*.

4. Disconnecting the receiving portions of the instrument from the transmitting portions, to assist the operator in transmitting, substantially as described.
